UNITED STATES PATENT OFFICE

HERMANN SCHUBERT, OF WALDWERK, NEAR NIEMES, CZECHOSLOVAKIA, ASSIGNOR TO
THE FIRM OF HUTTER & SCHRANTZ A. G., OF VIENNA, AUSTRIA

METHOD OF PRODUCING SEAMLESS CONNECTIONS OF THE ENDS OF METAL WIRE
GAUZE

Application filed July 16, 1929, Serial No. 378,811, and in Austria September 17, 1928.

I have filed applications in Austria on the 17th September, 1928, and 1st July, 1929, Czechoslovakia on the 25th September, 1928, and Germany on the 26th September, 1928.

5 This invention relates to a method of producing a seamless connection of the ends of metal wire gauze particularly for paper-making machines.

In order to produce an endless metal wire 10 gauze, particularly for paper-making machines, it is necessary to connect both of its ends either by a seam or without the provision of a seam.

In order to produce a seamless connection 15 it has been proposed to slide the warp-wire ends of one gauze-end, after the removal of its end-weft wire, into the other gauze-end in such a manner, that the inserted warp-wire ends are disposed alternately above and 20 below the end-weft wire of the other gauze-end, and subsequently the warp-wire ends of both gauze-ends are united with the common end-weft wire by welding or soldering.

The ends of the gauze have to be opened by 25 a tool in order to permit the insertion of the projecting inflected warp-wire ends of one gauze-end into the other gauze-end. This mode of opening the inflected warp-wire ends is very troublesome and takes up much time 30 and further a uniform opening of the inflected warp-wire ends is practically impossible so that, when sliding the ends onto the end-weft wire of the other gauze-end, irregularities cannot be avoided and thus the connection is not uniform.

According to one mode of carrying out the method according to the present invention this drawback is avoided by making the end-weft wire, which is taken out, harder and 40 somewhat thicker than the weft-wires of the remaining part of the gauze. Thereby the removal of this end-weft wire is facilitated, because the same is not undulated to such an extent as the normal weft wire of the gauze, 45 and further the last inflection of the warp-wire ends is sufficiently wide and uniformly opened. In order to facilitate the opening it is of advantage to cut off the warp-wire ends close to the end-weft wire which is removed. 50 This possesses the further favorable effect,

that the warp-wire ends, pushed onto and surrounding the end-weft wire of the other gauze-end, do not obstruct the openings of the mesh.

In order to prevent even the slightest projection of the inflected warp-wire ends of one gauze-end pushed onto the end-weft wire of the other gauze-end, beyond the gauze at the connecting place of the gauze-ends, it is of 55 advantage to roll down or depress the undulated warp-wire ends. Finally the warp-wire ends at both sides are hard-soldered or 60 welded to their common end-weft wire.

The above object of preventing unevenness 65 of the gauze at the place of connection can be attained in an improved way in the following manner:

The end-weft wire of the one end of the 70 gauze, onto which the projecting inflected warp-wire ends of the other end of the gauze 75 are pushed, is a metal wire which is thinner and harder than the weft wire of the remaining gauze, while the end-weft wire of the other end of the gauze, which is removed, is an ordinary weft wire.

In this manner the following effect is attained:

The warp-wire ends do not project beyond 80 the gauze at any place after their application. They can be pushed in a perfect manner onto the end-weft wire of the opposite gauze end, because the said end-weft wire is thinner than the ordinary weft-wire and the resistance or strength of the connecting place is safeguarded in view of its greater hardness. 85 After rolling down or depressing the applied inflected warp-wire ends on this end-weft wire, the said warp-wire ends will be disposed in the metal wire gauze somewhat deeper than the other inflections of the gauze. 90 Therefore the metal wire gauze is subjected at the zone of connection to less wear than the other parts of the gauze.

If for instance the normal weft-wires consist of tombac while the warp-wires are made of bronze, the end-weft wire of one gauze-end onto which the warp-wire ends of the other gauze-end are pushed will be a bronze-wire, 95 which is substantially of the thickness of the 100

warp-wire and thinner than the normal weft-wires of tombac.

Two modes of carrying out the present invention are illustrated by way of example on the accompanying sheet of drawings in which—

Figs. 1 and 2 show in longitudinal section the ends of the gauze to be connected, with and without an end weft wire respectively;

10 Figs. 3 and 4 illustrate in longitudinal section and plan view respectively the connected ends of the gauze;

Figs. 5 to 8 are like views of a modified embodiment;

15 Figs. 5 and 6 show in longitudinal section the ends of the gauze to be connected, with and without an end weft wire respectively; and

20 Figs. 7 and 8 illustrate in longitudinal section and plan view respectively the connected ends of the gauze.

The reference character 1 designates the warp-wires of one end of the gauze, 3 are the warp-wires of the other end of the gauze, 25 2 designates the last end weft-wire of one end of the gauze which remains in the latter, and 4 the last end weft-wire of the other end of the gauze which is removed. In the embodiment shown in Fig. 1, the end weft-wire 4 to 30 be removed is thicker and harder than the weft-wires of the other part of the gauze. In the embodiment illustrated in Figs. 5, 6 and 7, the end weft-wire 2 remaining in the gauze is thinner and harder than the weft-wire of 35 the other part of gauze. In Figs. 3 and 7, which illustrate in longitudinal section the connected ends of the gauze, the reference character 5 designates the places at which the ends of the warp-wires 3 are pushed onto and 40 soldered to the common end weft-wire 2.

I claim—

The method of producing a seamless connection of the ends of metal wire gauze particularly for paper-making machines, which 45 consists in removing the end-weft wire at one end of the gauze, pushing the projecting warp-wire ends onto the end-weft wire of the other end of the gauze so that they are disposed alternately above and below the said 50 end-weft wire, the said end-weft wire of the one end of the gauze, onto which the projecting inflected warp-wire ends of the other end of the gauze are pushed, being a metal wire which is thinner and harder than the weft 55 wire of the remaining part of the gauze, while the end-weft wire to be removed at the other end of the gauze is an ordinary weft-wire, forcing down the said applied inflected warp-wire ends onto the thinner and 60 harder end-weft wire, and subsequently firmly connecting the warp-wire ends at both sides with this common end-weft wire.

In testimony whereof I affix my signature.
HERMANN SCHUBERT.
